ANTOINE L. GIRARD INVENTOR.

BY

William E. Baff ATTORNEY.

UNITED STATES PATENT OFFICE.

ANTOINE L. GIRARD, OF WEST BOYLSTON, MASSACHUSETTS.

TOY.

1,378,022.

Specification of Letters Patent. Patented May 17, 1921.

Application filed February 19, 1920. Serial No. 359,909.

To all whom it may concern:

Be it known that I, ANTOINE L. GIRARD, a citizen of the United States of America, and a resident of the town of West Boylston, 5 county of Worcester, and State of Massachusetts, have invented a new and useful Improvement in Toys, of which the following is a specification.

This invention relates to improvements in 10 toy noise-makers and more particularly to improvements in a combination whistle and horn.

One of the objects of my invention is to 15 provide a combination noise maker which will be inexpensive to manufacture, and simple and efficient in operation.

A further object of my invention is to 20 devise a form of noise maker that shall be capable of making not only the noise or sound of a whistle but the sound of a horn as well.

A still further object of my invention is to 25 provide a noisemaker wherein there shall be combined two whistles and a horn both being blown into by means of one and the same mouthpiece.

Another object of my invention is to 30 provide an attractive noisemaker in which there shall be arranged two whistles of varying pitch and amplitude and in which there shall be located in the mouthpiece a horn, the whistles being mounted on a cross-piece.

The leading feature of my invention consists in enhancing the value of a noisemaker 35 by making it possible to obtain different sounds therefrom, and by enhancing the sanitary value of the device inasmuch as the whistles are not adapted to be placed directly in the mouth of the operator.

With the above and other objects in view 40 my invention consists in the arrangement, combination, and details of construction disclosed in the drawings and specification, and then more particularly pointed out in 45 the appended claims.

In the drawings wherein similar reference characters designate similar parts throughout the respective views,

Figure 1 is a top plan view of my invention,

Fig. 2 is a side elevation thereof,

Fig. 3 is a longitudinal sectional elevation thereof,

Fig. 4 is a cross-section through the horn 55 tube,

Fig. 5 represents two views at right angles to each other, one view in plan and the other in end elevation,

Fig. 6 is a side elevation of a modified form of my invention, 60

Fig. 7 is a front end view of Fig. 6,

Fig. 8 is an outer end view of Fig. 6,

Fig. 9 is an end elevation of another modified form,

Fig. 10 is a side elevation of Fig. 10, and 65

Fig. 11 is a perspective view of Figs. 9 and 10.

Referring to the drawings which are merely illustrative of my invention 1 designates the tubular portion of a horn which 70 may taper from large at its outer end to small at its inner end. A cross-piece or **T** is formed integrally upon or otherwise connected at right angles upon the end of the tubular portion 1 of the horn, and this **T** 75 extends preferably the same distance from the tubular portion 1 as a center or axis. A pair of tin or other metallic or paper whistles are arranged to be connected to the opposite ends of this cross-piece or **T**. Each 80 of these whistles is shaped in exactly the same manner, and is made preferably of pressed metal so shaped and positioned that they will fit the open ends of the **T** 2. Each whistle furthermore is composed of two sections, one of which projects into the tubular **T** 2 and the other of which projects therebeyond. Each whistle has two concentric 85 alining openings 10, and 10^a through which air is adapted to be blown in the act of blowing the whistles.

One of the whistles is designated A and the other whistle is designated B. 3 designates the outer section of one whistle and 5 the inner or other section thereof. 4 designates the outer section of the other whistle while 6 designates the other section thereof. 95

As shown in Fig. 1, the mouthpiece 7 is secured upon the tubular portion and is made of wood or similar material. The 100 tubular portion tapers in the direction of the mouthpiece, while its larger end is directly connected to the **T** connection as at C, communicating in this manner with the hollow portion of the **T** connection.

The metallic horn flap or reed 8 is located 105 in the tubular portion which is adapted to be flexibly offset against the impact of air blown forcibly in the direction of the mouthpiece but failing to respond to sound when 110

the air is thus blown because it is necessary to strain this flap by blowing air directly against this flap in the direction of the T shaped body 2. It will be seen that the mouthpiece fits snugly and frictionally around the tubular portion of the horn, the hollow portion of this mouthpiece being designated 7 as illustrated in Fig. 3. It will be understood that the flap 8 virtually covers entrance of foreign matter into the tube 1 of the horn.

The entire appearance and arrangement of the noise maker is that of a strong yet light attractive T-shaped body. When it is desired to use this noisemaker, the user will place the mouthpiece of the same between his lips and blow into the same and in this manner will sound the reed of the horn as is true with any horn blown in the same manner. By inspiring the air through the whistle ends of the crosspiece of this noisemaker and out through the mouthpiece, into the operator's mouth either or both whistles may be sounded. One whistle may be designed to respond against slight air inspiration, while the other whistle may be made to respond against an unusually strong inspiration, etc., the aim being at all times to obtain three distinct sounds or noises, two whistles and one horn. The air may be blown out of the mouthpiece in order to obtain the very best results.

There is shown in Fig. 6 a modification of a horn and whistle, as in this case the horn and whistle are formed in one piece, 11 designates the wooden mouthpiece and covers the horn flap or reed 15 located in the tube 12 of the horn, a band or tape of red, white and blue is preferably wound upon this tube throughout its length. A single whistle device made of two sections is secured at the outer end of this tube and has the air hole 14 formed therein through which air may be forcibly blown.

A still further modification of my invention is illustrated in Figs. 9, 10 and 11. In Fig. 9 there is disclosed the long T-shaped portion 17 of the sounding tube and this body projects at right angles to form a nipple which projects into the pocket 16 of the rubber suction bulb 15 as clearly illustrated in the figures aforesaid. The nipple 23 is preferably made of thin metal as is the tubular portion 17 and the tubular pocket 16 is formed upon the rubber bulb so as to have a press fit upon the nipple. By taking hold of the rubber bag 15 and squeezing the same air may be forcibly ejected out of the tubular portion 17 so as to emerge through the two oppositely arranged whistles 18 and 19 and sound the horn as hereinbefore set forth. Both forms of my invention are practical efficient devices and will produce desirable noises from one and the same instrument.

Numerous changes may be made in prac-

tice without departing in principle from the details of construction herein disclosed.

What I claim and desire to protect by Letters Patent is:—

1. A noisemaker formed on a single piece of tubular metal, one part of which extends at right angles with respect to the other, and a horn carried by said tubular member and a whistle carried by said right angularly projecting member. 75

2. A noisemaker formed of a piece of tubular sheet metal, another tubular piece of metal extending as a T in communication with said tubular sheet metal, a pair of whistles arranged at the opposite ends of 80 said T connection, and a mouthpiece secured to said tubular piece of metal.

3. A noisemaker formed with a cross piece T-shaped in configuration, the long tube of 85 said noisemaker receiving air, and expelling it through the cross-piece thereon, whistles carried by said cross-piece therein, and a mouthpiece secured upon said long tube.

4. A device as described consisting of a tubular stem, a tubular cross-piece connected 90 thereupon and extending an equal distance from opposite sides of said stem, a whistle located in each end of said tubular cross-piece, and a mouthpiece secured upon said stem and having its tubular portion projecting 95 therebeyond.

5. In combination, a tubular stem having a tubular cross-piece formed thereupon, a pair of whistles carried in the opposite ends of 100 said cross-piece, and a mouthpiece secured upon the inner end of said tubular stem, the mouthpiece carrying a horn concealed therein.

6. In combination a tubular stem provided with a tubular cross-piece, a pair of whistles located within said cross-piece at outer ends 105 thereof, a horn valve secured at the opposite end of said tubular stem, and a wooden mouthpiece secured upon said tubular stem, the whistles having holes arranged concentrically and being also in alinement, said valve being located so as to sound said horn only when a blast is blown into said mouthpiece. 110

7. A noise-maker consisting of a horn, and 115 whistles connected at either side of said horn, and a common mouthpiece carried by said horn through which air may pass to operate said horn and said whistles, said horn being sounded by blowing air into said 120 mouthpiece and said whistles by blowing air out of said mouthpiece.

In witness whereof I have hereunto set my hand and affixed my seal this 18th day of February, 1920.

ANTOINE L. GIRARD. [L. S.]
